CLAIM

The ornamental design for a display screen with graphical user interface as shown and described.

DESCRIPTION

FIG. 1 is a front view of a display screen with graphical user interface showing the claimed design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of an eighth embodiment thereof; and,

FIG. 9 is a front view of a ninth embodiment thereof.

The dot-dashed broken lines depict the display screen. The remaining broken lines depict portions of the graphical user interface. The broken lines form no part of the claimed design.

1 Claim, 9 Drawing Sheets
